ELECTRODE GAS REMOVAL METHOD AND APPARATUS

Application filed December 29, 1927, Serial No. 243,291, and in Germany January 10, 1927.

This invention relates to the removal of gases occluded in electrode materials commonly used in thermionic and like vacuum tubes, particularly desirable in those tubes employing high vacuum.

It is well known that in order to obtain a high vacuum in vacuum tubes that will remain permanent it is necessary to free the materials of which the electrodes are made of their occluded gases during the vacuum pumping process and before the tubes are sealed, and this must be done irrespective of the character of the material, usually metal, of which the electrodes are composed.

15 This electrode gas removal has always been one of the exacting difficulties in the manufacture of thermionic and like discharge tubes where the tube is intended to be so employed that its vacuum should be 20 permanently maintained at the highest possible value.

25 Various methods have been devised for carrying out this electrode de-gassing and the art has succeeded in producing tubes capable of maintaining in use a very high vacuum. However, methods heretofore employed are complicated and expensive, or else affect the physical and electrical characteristics of the electrodes, especially coated cathodes, to an undesired extent with the result that these vital parts of the tube initially suffer from the de-gassing process.

30 According to the present invention, it is possible to obtain a high degree of de-gassing of the electrodes in vacuum tubes without any of the disadvantages and ill effects of previous methods. The present method principally consists in introducing into the tube or container, which has first been evacuated to a desired degree with the customary pumping means, a small quantity of a non-absorbable gas, in particular an inert gas, examples of which gases are argon, neon, crypton and helium, and producing in 35 the presence of this introduced gas an electric discharge between the several electrodes with the aid of suitable electrical potentials applied to the electrodes under treatment. With the proper selection of the gas pressure and the potentials an ionic bombard-

ment of the electrodes under treatment will produce sufficient heat in them, such as a full glow, to cause them to easily expel their occluded gases into the surrounding atmosphere of inert gas. During the discharge, or subsequent to its interruption, the gas mixture thus produced is withdrawn from the container with the aid of the vacuum pump. Usually it is sufficient to fill the container but once with the inert gas, but if particularly high degrees of permanent vacuum are being sought the operation may be repeated one or more times.

35 The method is economical from the point of view of inert gas consumption since satisfactory discharge conditions can be obtained with a pressure of inert gas of the order of 1 millimeter. The pumping and electrical apparatus required is very simple and of a kind readily available in organizations making tubes.

40 The method is of particular advantage in the manufacture of thermionic tubes, such as transmitting and receiving tubes for radio. One effective way of de-gassing such tubes consists in bombarding the electrodes with the aid of the electron emission from the heated filament or cathode. This procedure, however, involves the objection that the ions present during the continuance of 45 the discharge bombard the filament or cathode quite violently, with the result that it suffers some destruction which at least shortens its useful life and which, in the case of 50 highly active or emissive cathodes, decreases their emissive quality.

45 To avoid the destructive effect of ionic bombardment of the more or less fragile cathodes, simple expedients may be resorted to. Thus the bombarding discharge may be produced between electrodes which are not cathodes, and the necessarily present cathode be protected from the ionic movement through the aid of ion repelling potentials applied thereto; or, the cathode may be heated in the normal way to create thereabout a cloud or field of electrons whose negative charge will sufficiently neutralize the positive ions attempting to approach the cathode. Again, the cathode may be pro-

- ected by applying a protecting potential to another properly located electrode, for instance, the grid, when the bombarding discharge is produced between other electrodes.
- 5 If sufficient electrodes are not available in the construction of the tube, one or more auxiliary electrodes may be deliberately inserted therein for the purpose of facilitating the process, though such auxiliary electrode 10 may not thereafter be needed in the ordinary functioning of the tube.
- If the electrodes are of more or less widely different dimensions, or otherwise constituted so that one contains a considerable 15 quantity of occluded undesirable gas and the other contains little of such gas, it is sufficient to use the electrode containing the greater quantity of gas as the cathode in the bombarding process, but such procedure is 20 necessarily limited to direct current bombardment; in other words, it is a one-way process. If there are two electrodes each containing large amounts of gas, as by having 25 large masses, a complete de-gassing of these electrodes can be obtained by commutating or periodically reversing the potential applied to them from a direct current source, or an ordinary alternating current source may be depended upon.
- 30 It is of course understood that tubes degassed by the procedure outlined in this invention may receive a final clean-up treatment according to any of the well known 35 clean-up processes employing so-called getter materials.
- The method and apparatus employed will be further understood by reference to the figures of the accompanying drawing in 40 which like reference characters represent like parts so far as possible throughout the several figures.
- Fig. 1 shows the method applied to an ordinary three-electrode vacuum tube.
- 45 Fig. 2 shows the method applied to an ordinary three-electrode vacuum tube in which an auxiliary anode is introduced.
- Fig. 3 shows the method employed in a 50 three-electrode tube having two grids.
- Fig. 4 shows the method employed in connection with an ordinary two-electrode tube 55 having two anodes for so-called "full-wave" rectification.
- Referring to Fig. 1, VT is the ordinary 60 glass or like container for a vacuum tube shown alternately connectable to a vacuum pump and a source of inert gas by means of the two-way cock V through the communicating stem K. The tube is shown to include, in well known form of construction 65 and support on a stem S, a filament F, a grid G and a plate P. A potential is shown applied between the grid G and the plate P from a source B₁, which may be a battery or other suitable source of potential, the 70 magnitude of potential being controllable

through the variable resistance R. The negative side of the source is shown connected to the plate P so that in this case the plate acts as a cathode, which is in accordance with the previous comments as to a procedure 75 when one electrode, such as a plate of large mass, is being worked with another electrode, such as a grid, with small mass. Battery B₂, or like source of potential is shown connected between the grid G and the 80 filament F, the negative side of the source being connected to the filament, thus to apply a negative potential to the filament with respect to the grid to protect it from ionic bombardment as previously discussed. The 85 potential can be readily applied or removed by means of the switch N. With the arrangement shown the tube VT can be pumped to a high degree by proper adjustment of the cock V, after which the desired amount of inert gas is permitted to enter 90 through movement of the same cock. The potential of B₁ is then applied to create the desired discharge, which discharge is regulated in intensity by the resistance R. 95 When the electrodes under treatment have reached the necessary temperature for the particular material to expel the occluded gases, which condition is generally indicated by a full red glow, the discharge may be 100 interrupted and the vacuum pump then applied to remove the resulting mixture of gases. During the process the switch N may be closed to apply the protecting potential to the filament. If the operation is not to be 105 repeated the tube is then sealed off at the base of the communicating stem K when the vacuum pump has produced the desired degree of vacuum. The final clean-up by the getter process may be completed before the 110 sealing off or after, depending upon the particular clean-up process employed.

Fig. 2 differs from Fig. 1 in that an auxiliary electrode A is included in the electrode structure of the tube, and a source of potential S₁ is shown connected between this auxiliary electrode and/or the grid, the two being 115 shown cross-connected in the figure. In this case the discharge between these two electrodes may be obtained by means of an alternating current, or a commutated or periodically reversed direct current, so that the electrodes alternately act as cathodes, this procedure being previously discussed. The figure also shows the secondary winding S₂ 120 of an alternating current transformer connected across the terminals of the filament F to heat this filament to produce a cloud of electrons thereabout as a protection against 125 ionic bombardment.

The details of the vacuum pump and inert gas connection are omitted in Fig. 2 and the succeeding figures for brevity, it being understood that they are the same as in Fig. 1, or equivalent connections.

Fig. 3 differs from Fig. 1 in that an electrode structure is shown which includes two grids, one being shown inside of the other. In this arrangement the connections for producing the discharge are made between the plate P and the outer grid G₁. There are shown means for applying a potential to the inner grid G₂ that is positive to the outer grid G₁, which potential acts to protect the cathode passing through the inner grid from ionic bombardment.

Fig. 4 shows a form of tube commonly employed for rectifying alternating currents, the two plates P₁ and P₂ cooperating with the single filament F to produce what is commonly termed "full-wave" rectification. The arrangement shows means for connecting a potential S₁ between the two plates P₁ and P₂ to produce a discharge therebetween that alternately requires each of the two plates to serve as cathodes. Of course, direct current may be used wherein one plate is bombarded for a time and the operation then shifted so that the other plate is bombarded for a time, and this is also true of all of the figures where alternating current sources of potential have been indicated. There is also shown the secondary winding S₂ of a transformer connected across the terminals of filament F, or filaments if there be more than one, for heating the same to produce a cloud or field of electrons thereabout for protection against ionic bombardment. Of course, direct current may be used for heating the filament in this and the other figures of the drawing.

While we have shown and described specific arrangements for employing our invention, we do not desire to be limited by the particular arrangements chosen merely for illustrative purposes, and our invention is of the scope set forth in the annexed claims.

Having thus fully described our invention, we claim:

1. In the practice of fabricating thermionic and like discharge tubes, the method of de-gassing the included electrodes in the presence of an electrode subject to injury by ionic bombardment which consists of evacuating the tube, admitting a quantity of inert gas, producing an ionic discharge with the aid of said gas and applied potential between chosen electrodes other than the electrode subject to injury sufficient to produce by bombardment a gas expelling temperature in said electrodes, shielding said electrode subject to injury during said discharge by maintaining around said electrode an electric charge positive to that of said electrode, and further evacuating the tube of the resulting gas mixture.

2. In the process of de-gassing electrodes by ionic bombardment, the method of protecting a present electrode subject to injury by such bombardment which consists in

causing the bombardment to take place in an atmosphere of inert gas at a pressure which permits a low voltage ionic discharge between the electrodes to be de-gassed and so charging the electrode to be protected during the bombardment process that the ions are diverted therefrom.

3. In the process of de-gassing electrodes by ionic bombardment in the presence of an electrode subject to injury by such bombardment, the method of protecting said electrode from destructive bombardment which consists of interposing between said electrode and the region of ionic activity an electrode so electrically charged with respect to said protected electrode that the ions are prevented from substantive bombardment of said protected electrode.

4. In the process of fabrication of vacuum tubes having an anode, grid, and cathode, the steps of evacuating the envelope of said tube, introducing a small quantity of inert gas therein, producing a potential gradient between said cathode and said anode, and maintaining said grid at a potential more positive than either said anode or said cathode, whereby said cathode is substantially protected from ionic bombardment.

5. In the process of fabrication of vacuum tubes having an anode, a grid and a cathode, the steps of evacuating the envelope of said tube, introducing therein a small quantity of inert gas, producing a potential gradient between said cathode and said anode, maintaining said grid at a potential more positive than either said anode or said cathode, whereby the anode is subjected to a greater degree of bombardment than said cathode, and evacuating the mixture of the inert gas and the gases expelled from said electrodes and refilling said envelope with inert gas to the desired pressure.

6. In the process of fabrication of vacuum tubes having an anode, a grid, and a cathode, the steps of evacuating the envelope of said tube, introducing a small quantity of inert gas therein, producing a potential between said anode and said grid, said grid being more positive than said anode and producing a potential upon said cathode more negative than said grid, whereby the cathode is protected from ionic bombardment.

7. The process of degassing a normally cold electrode in the presence of an oxide coated cathode which consists in applying voltage between said electrode and another cold electrode, other than the oxide coated cathode, to cause the said electrode, to act as a cathode and be subjected to ionic bombardment, causing the bombardment to take place in an atmosphere of inert gas at a pressure which permits a low voltage ionic discharge, and protecting the oxide coated cathode from bombardment by maintaining

an ion repelling means in proximity thereto.

8. The process of degassing a normally cold electrode in the presence of an oxide coated cathode which consists in applying

5 voltage between said electrode and another cold electrode, other than the oxide coated cathode, to cause the said electrode to act as a cathode and be subjected to ionic bombardment, causing the bombardment to take

10 place in an atmosphere of inert gas at approximately one mm. of pressure, and protecting the oxide coated cathode from ionic bombardment by maintaining an ion repelling charge in proximity thereto.

15 9. In combination a discharge tube containing an inert gaseous medium at approximately 1 mm. of HS pressure, an oxide coated electrode and two cold electrodes, connections between said cold electrodes and

20 a voltage source adapted to cause a luminous discharge in said inert medium across said cold electrodes, and connections to said oxide coated electrode adapted to create a charge thereabout which is repellent to ions

25 from said luminous discharge.

10. The method for de-gassing a discharge tube having three electrodes which are normally cathode, anode and grid, respectively, which comprises the steps of eva-

30 cuating the tube, filling the tube with inert gas at a predetermined pressure, and applying potentials to said electrodes with the grid sufficiently positive relative to the anode to cause an ionic discharge between

35 the grid and anode, and with the cathode charged relative to the grid to prevent substantial bombardment of said cathode.
